UNITED STATES PATENT OFFICE.

WILLIAM H. MORGAN, SR., OF ALLIANCE, OHIO, ASSIGNOR TO WILLIAM H. MORGAN, JR.,
OF ALLIANCE, OHIO.

CENTRIFUGAL PIPE MOLD.

Application filed October 23, 1926. Serial No. 143,637.

This invention relates to an improvement in pipe molds employed in centrifugal casting of cast iron pipes and it consists broadly in a mold made up of a series of independent 5 units of comparatively small size, each unit having a flanged end secured by screw threads, bayonet joints or other detachable integral means to a flanged end of the next adjacent unit, so that any one or more units 10 can be readily removed for replacement without disassembling the entire mold.

In the accompanying drawings;

Figure 1 is a view in elevation of a section of the mold,
15 Figure 2 is a view in longitudinal section,
Figure 3 is a view in end elevation,
Figure 4 is a view of a modification.
These molds are intended to be cooled by a water jacket around the outside, but as 20 I make no claim to any feature of the apparatus but the mold, I have not shown the water jacket or any means for rotating the mold or feeding the cast metal into the mold.

The mold, is as shown in Figures 1 and 2 25 made up of a series of cylindrical units 4 of comparatively small width, and each is provided at one edge with a flange 5, threaded internally as at 6, to engage corresponding threads on periphery of the recessed seat 7 in the next adjacent section or 30 unit. I prefer to make the flanges 5 in the form of a double flange or step as clearly shown in Figure 2, the inner face of the outer step 8 of the flange being smooth or 35 plain as at 9 and closely embracing the outer step 10 of the next adjacent unit.

Each section of the mold except the outer end sections are flanged at one end of its periphery and recessed at the opposite edge, 40 except the end sections, which of course are only flanged on their inner faces. With such a construction, a strong rigid self supporting mold is formed, the construction being such that any section can be removed 45 by clamping one section and turning the other.

In the construction shown in the modification Figure 4, the laminations or rings 4^a are provided with a single step, instead of 50 two as shown in Figure 2, and are threaded externally to be engaged by the internally threaded annular rings 10^a which as shown are provided on their inner faces with a U-shaped groove which latter rests over the 55 joints between the laminations or rings.

By making the rings U-shaped in cross section they act as springs to permit of expansion and contraction of the molds.

From the foregoing, it will be seen that in the construction shown in Figures 1 and 2 the connecting means are internal, that is, 60 are wholly within the outer periphery of the mold, whereas in Figure 4 the connecting means are external and exposed.

While I have referred to units or sections 65 connected by threads, it is evident that they may be connected by bayonet joints, or other means so that the lamination sections or units are connected so that any unit or units 70 may be removed without disconnecting or separating the other sections.

Among the many advantages of this construction are the following:

1. These laminations being comparatively 75 of small size can be machined and heat-treated uniformly so as to secure the same quality of material throughout the length of the mold.

2. By reducing the mold to a series of narrow laminations the longitudinal thermal 80 stress set up by the molten metal on the interior of the mold is broken up into such small pieces that the stress does not exceed the elastic limit of the metal used. In other words, when the mold is in one long piece, 85 these stresses are cumulative and result in the breaking down of the steel, as this stress becomes several times the elastic limit of the material.

3. The use of the laminations joined together in the method disclosed permits of certain flexibility in the mold, allowing it to conform to the stresses set up by the rotation and application of internal heat.

4. Should any of the rings deteriorate in 90 service, new rings can be readily substituted in the portion damaged without necessitating throwing away the entire mold, as must now be done with a single-piece mold. This can be done without danger of throwing the 95 mold out of balance or alignment as would be the case with other forms of laminated molds where the whole mold must be torn down in order to replace part.

5. It may be found in actual practice that 100 it will be desirable to make certain zones of this mold of special steel in order to withstand the excessive temperatures developed at these particular parts. With this improvement it will be readily seen that this 105 110

can be done, as the quality of the steel in laminations can be varied to suit the temperature conditions found in the various portions of the mold.

5. 6. In order to compensate for the various temperatures existing in the mold during casting, the laminated construction permits of varying the thickness of walls between the internal and external or cooled portions 10 so that the metal being cast will be cooled more rapidly at certain points and especially the end which is poured last. This permits the pipe to be cooled and stripped more rapidly than with a mold of uniform thickness 15 as at present used.

It is evident that many slight changes might be resorted to in the relative arrangement of parts shown and described without departing from the spirit and scope of my 20 invention hence I would have it understood that I do not wish to confine myself to the exact arrangement of parts shown and described but, having fully described my invention what I claim as new and desire to 25 secure by Letters Patent, is:—

1. A metal mold for casting pipe, consisting of a series of end units or rings and intermediate units or rings each flanged at one side of its periphery and recessed at the 30 other side, the flanged and recessed portions having means for detachably securing the sections together whereby any one unit of the mold may be disconnected from its adjacent section or sections without loosening or 35 disconnecting the units of the other section or sections.

2. A metal mold for casting pipe consisting of a series of units or rings, each, except 40 the end sections, being provided at one edge of its periphery with an internally threaded flange adapted to engage a threaded recessed seat in the adjacent section whereby any one unit of the mold may be disconnected from its adjacent sections without

loosening or disconnecting the units comprising the other sections. 45

3. A metal mold for casting pipe, consisting of a series of end and intermediate units or rings, each intermediate unit or ring having stepped flanges adapted to enter a 50 similarly shaped recess in the adjacent unit, one of the steps of each of the stepped flanges being threaded to engage threads in the recessed portion of the adjacent unit whereby any one unit of the mold may be disconnected from its adjacent section or sections of the mold without loosening or disconnecting the units of the other section or sections. 55

4. A metal mold for casting pipe, consisting of a series of end and intermediate units or rings each intermediate unit or ring having a stepped flange adapted to enter a similarly shaped recess in the next adjacent unit, one of said steps and the corresponding part of the recess of the adjacent section carrying means for detachably connecting the sections, the other step of the flange and recess being plain and adapted to snugly fit one within the other whereby 60 any one unit of the mold may be disconnected from its adjacent section or sections, without loosening or disconnecting the units of the other section or sections. 65

5. A metal mold for casting pipe consisting of a series of end and intermediate units or rings each intermediate unit or ring having a stepped flange adapted to enter a similarly shaped recess in the next adjacent section, one of the steps in the flange and the 70 corresponding step in the recess being screw threaded and the other step in the flange and recess being plain and snugly fitting one within the other. 75

In testimony whereof, I have signed this specification.

WILLIAM H. MORGAN, Sr.
